UNITED STATES PATENT OFFICE.

ADAM A. SERVA, OF CANTON, OHIO, ASSIGNOR TO THE UNITED ELECTRIC COMPANY, OF CANTON, OHIO, A CORPORATION OF OHIO.

SUCTION CLEANER.

Application filed November 3, 1923. Serial No. 672,624.

This invention relates to suction cleaners commonly used for cleaning carpets and floors, in which the cleaning action is performed by air currents caused by suction in- 5 to the mouth of the nozzle or tool of the machine, which may be supplemented by a brush serving to sweep the surface over which the cleaner is moved.

In machines of this character, the cleaning mouth of the nozzle or tool usually comprises an elongated slot or opening which may have a substantial width, the rim thereof being normally held in sealing contact with the carpet, compelling the air to pass 10 through the carpet to the mouth; and when the contact between the rim and the carpet is broken, a portion or all of the air may pass over the carpet and beneath the rim of the mouth.

20 The objects of the present improvement are to provide means in the mouth of the nozzle or cleaning tool, adjacent to and parallel with each lip of the rim of the mouth and arranged to be alternately protruded from the plane of the lips for causing the carpet to impinge the same and the rearmost lip of the mouth, and raising the forwardly moving lip of the mouth free of contact with the carpet or floor for the 25 full width of the nozzle or tool for receiving surface dirt, and other refuse which are dislodged by the brush and the in-rushing air.

30 The above and other objects may be attained by shaping the mouth of the nozzle or cleaning tool in the form of an elongated opening or slot, a shaft being journaled through the longitudinal center of the nozzle and carrying two longitudinal brushes located adjacent to the forward and rear 35 lips of the mouth; means being provided for rocking the shaft by the operation of the cleaner upon the floor or carpet, whereby each brush is alternately protruded below the adjacent lip of the mouth, when the same becomes the forward lip in the movement of the nozzle, permitting the air to be drawn beneath said lip and into the mouth, causing surface dirt to be dislodged and 40 drawn into the mouth with the in-rushing air, the carpet being substantially sealed across the mouth between the brush and the rearmost lip, compelling the air to be drawn through the carpet between the same.

The invention thus set forth in a general 55 way may be embodied in the form of a device illustrated in the accompanying drawings, forming part hereof, in which-

Figure 1 is a fragmentary side elevation of a vacuum cleaner embodying the invention, the nozzle being shown in section, showing the position of the brushes upon the forward movement of the cleaner;

Fig. 2, a similar view showing the position of the brushes upon the rear movement of the cleaner;

Fig. 3, a bottom plan view of the mouth of the cleaner, parts being broken in section; and

Fig. 4, a detail perspective view of one 70 member of the spring clutch.

Similar numerals refer to similar parts throughout the drawings.

The casing of the machine includes the cylindric fan chamber 1 and the forwardly 75 extending vacuum chamber 2 below the fan chamber and communicating therewith in the usual manner, for exhausting air from the vacuum chamber into the fan chamber through the action of the usual fan which may be driven in any usual manner as by an electric motor 3.

The nozzle 4 communicates with the forward end of the vacuum chamber, being transversely elongated upon opposite sides 85 thereof and arranged to be supported upon or adjacent to the carpet A by means of the usual wheels 5 and 6. The elongated mouth of the nozzle includes the front and rear lips 7 and 8 respectively.

90 A pair of longitudinal brushes 9 and 10 are connected in parallel relation by the plates 11 and 12 forming an oscillatable frame. The plate 11 is provided with a cylindric bearing member 13 which may be 95 journaled upon the spring pressed pintle 14 carried in one end of the mouth, the plate 12 having a friction disk 15 upon its outer side and being provided with the journal member 16 journaled in the bearing sleeve 17 upon the end of the rotatable shaft 18, which is provided with a pulley 19 connected by the belt 20 with the adjacent wheel 5.

100 The sleeve 17 is provided with the spring fingers 21 which frictionally engage the friction disk 15 upon the plate 12. Stop pins 22 and 23 are provided in the front and rear

portions respectively of the mouth and arranged to limit the downward movement of the brushes 9 and 10 respectively.

When the cleaner is moved forward upon the floor, as shown in Fig. 1, the action of the belt 20 will lower the forward brush 9, protruding the same beneath the plane of the nozzle and into engagement with the carpet, the pin 22 limiting the downward movement thereof and preventing the spring clutch from further rotating the brushes, while the rear brush 10 will be raised above the plane of the rim of the nozzle.

The rear lip 8 will thus be held in sealing contact with the carpet when the same is drawn up by the reduced pressure within the nozzle and the front lip 7 will be held out of contact with the carpet by means of the forward brush 9.

20 The strong suction of the fan will thus draw cleaning currents of air from under and through the carpet between the brush 9 and the rear lip 8, while a positive air current will be drawing under the forward lip 7 of the mouth along the surface of the carpet, for not only drawing in particles of refuse, but sweeping over the surface of the carpet under the front lip of the nozzle.

As the movement of the cleaner upon the floor is reversed, the forward brush will be raised and the rear brush lowered into engagement with the carpet, permitting sealing contact between the rear brush and forward lip and holding the rear lip out of contact with the carpet.

Thus as the cleaner is moved in each direction upon the carpet, the brush upon the adjacent side of the nozzle will hold the adjacent lip out of engagement with the carpet, permitting air currents to be drawn over the surface of the carpet and under said lip, while the other lip is held in sealing contact with the carpet and the brush which is in lowered position, will sweep the surface of the carpet over which it passes.

45 The fan serves to maintain a constant suction through the cleaning mouth, and when the same is applied to a carpet or other fabric, the power is so proportioned that in addition to drawing cleaning currents of air from under and through the carpet, a locally intensified current of air is drawn under the lip of the nozzle upon the side toward which the cleaner is moving, over the

surface of the carpet and within the mouth of the cleaner, and by carrying all the dust and surface litter immediately to and through the exhaust orifice, the formation of inactive air pockets in either side of the nozzle is prevented, consequently preventing settling of dust and dirt therein.

I claim:—

1. A suction cleaner casing having an elongated mouth with rim lips adapted to be presented to a carpet or the like, an oscillatable frame mounted in the mouth, a brush mounted upon the frame adjacent to each of the elongated lips, a pulley, spring fingers operatively connected to the pulley and frictionally engaging the frame, a belt connected to the pulley for rotating the same by the movement of the cleaner upon the floor, whereby one brush is held in contact with the carpet as the cleaner is moved in one direction and the other brush is held in contact with the carpet as the cleaner moves in the opposite direction.

2. A suction cleaner casing having an elongated mouth with rim lips adapted to be presented to a carpet or the like, an oscillatable frame mounted in the mouth, a brush mounted upon the frame adjacent to each of the elongated lips, a pulley, a shaft fixed to the pulley, a sleeve fixed upon the shaft, a plurality of spring fingers upon the sleeve frictionally engaging the frame, a belt connected to the pulley for rotating the same by the movement of the cleaner upon the floor, whereby the forward brush is held in contact with the carpet as the cleaner moves forward and the rear brush is held in contact with the carpet as the cleaner moves rearward.

3. A suction cleaner casing having an elongated mouth with rim lips adapted to be presented to a carpet or the like, an oscillatable frame mounted in the mouth, a brush mounted upon the frame adjacent to each of the elongated lips, a pulley frictionally connected to the frame, a belt connected to the pulley for rotating the same by the movement of the cleaner upon the floor, whereby one brush is held in contact with the carpet as the cleaner is moved in one direction and the other brush is held in contact with the carpet as the cleaner moves in the opposite direction.
